UNITED STATES PATENT OFFICE.

HENRY J. GAISMAN, OF NEW YORK, N. Y.

SUSPENDERS.

No. 820,486.

Specification of Letters Patent.

Patented May 15, 1906.

Application filed July 17, 1903. Serial No. 165,921.

To all whom it may concern:

Be it known that I, HENRY J. GAISMAN, a citizen of the United States, residing in New York city, borough of Manhattan, State of New York, have invented certain new and useful Improvements in Suspenders, of which the following is a specification.

The object of my invention is to provide improved means for connecting suspenders with trousers, and has for its object to permit the suspenders to be connected with the waistband or trousers independent of or in conjunction with the waistband-buttons, to permit adjustment of the straps or webbing at different points with respect to the line of the waistband, to permit the ready connection and disconnection of the straps with the suspender ends or bars, and to permit the adjustment of the holding-clamps with respect to each other and the buttons on trouser-waistbands.

To the foregoing and other ends my invention comprises the novel details of improvement and arrangements of parts that will be more fully hereinafter set forth and then pointed out in the claims.

Reference is to be had to the accompanying drawings, forming part hereof, wherein— Figure 1 is a face view of a pair of suspenders embodying my invention. Fig. 2 is a detail side view enlarged and partly in section. Fig. 3 is a detail enlarged view of part of one of the suspender ends or bars. Fig. 4 is an edge view thereof. Fig. 5 is a section on the line 5-5 in Fig. 3 looking in the direction of the arrows, and Fig. 6 is a plan view of one of the suspender-end bars.

Similar numerals of reference indicate corresponding parts in the several views. The suspenders are indicated generally at 1 and may be generally of suitable or usual construction, my improvements being directed to the means for connecting the suspenders with the trousers. Instead of the conventional ends or tabs usually employed I provide bars 2, adapted to extend along a waistband, and at their ends said bars are provided with clamps or clips 3, adapted to grasp or grip the trouser-waistband. In the drawings said clamps or clips are shown in inverted-U form or yokes adapted to straddle the waistband edge, and they are shown

provided with springs 4 and levers 5, adapted to grip the waistband. The lever 5 is pivotally supported on the clamp 3 at 5^a and has a projection 5^b to press the spring 4 against the waistband to clamp it against the wall 3^a. When the lever 5 is swung to the position shown in Fig. 4, the waistband will be gripped, and when said lever is swung reversely the spring 4 will release the waistband, but any other suitable clamp adapted to grip the waistband may be used. As shown, the clips 3 are connected near their lower portions with the bar 2, whereby when said clips are placed upon and receive the edge of the waistband the bar 2 will be hidden behind the waistband, as well also as the loops 11, more or less. As illustrated, one of the clamps or grips 3 is secured to each bar 2, and the other is adjustable along said bar to vary the distance between said clamps or grips. To this end I have shown one clamp 3, provided with a sleeve 6, mounted to slide on the bar 2 and having a slot 6^a, receiving a pin or projection 2^a from bar 2, so that sleeve 6 and clamp 3 may be adjusted along bar 2, but rotation with respect to bar 2 is prevented, whereby both clamps 3 on a bar are maintained in substantially parallel relation. By this means the clamps can be adjusted with respect to the positions of corresponding buttons on the waistband. To enable the clamps to engage with the shanks or holding-threads of buttons located on the outer surface of the waistband, I provide the clamps with sockets or recesses 3^b, into which the shanks or holding-threads may pass. Such sockets may be in one of the edges of the front wall 3^a of the clamp or grip. By this means the clamps may be connected with the button-shanks in addition to the clamping action of spring 4 and lever 5, and when so adjusted the front wall 3^a of the clamp which overlies the waistband is more or less hidden by the button. By having the sockets 3^b in the sides of the clamps the vertical strain on the button-shanks is borne by the clamp, and the gripping of the clamp upon the waistband is relieved. The adjustment of one of the clamps along bar 2 enables ready application of two clamps with respect to corresponding buttons.

The bar 2 is preferably detachably connect-

ed with the suspender straps or webbing. To this end I have shown the suspender-straps provided at their ends with connecting devices comprising a lever or clip 7, pivotally connected with a hanger 8, carried by the suspender, as by a loop 9, and the clip 7 is connected with bar 2 preferably by means of a loop or link 11, hung on said bar and provided with an eye 11^a to receive said clip. 10 Such arrangement permits ready detachment of the suspenders from the bars 2, while the bars may remain attached to the waistband.

As shown in the plan view in Fig. 6, the bar 2 is curved in the direction corresponding to 15 curvature of a wearer's waist, and the clamps 3 are on the outer or convex side thereof. Such arrangement permits the bar to lie snugly within a waistband, and particularly by having the bar 2 curved so that its central 20 portion lies substantially on a line *a* passing through the two clamps 3, the latter are kept from twisting or turning over under the strain coming on the clamps during use, whereby the clamps and bar remain in proper positions. The bar 2 is preferably made adjustable laterally with respect to the straps of the 25 suspenders, and to permit such loop 11 to remain in adjusted position along bar 2 I provide the latter with several pins or projections 2^b, preferably on the lower edge, between two of which projections the loop 11 lies to prevent it from sliding along the bar. To permit adjustment of loop 11 along the 30 bar 2, the bore or bearing of said loop is enlarged at one side substantially like a key-hole-slot, as at 11^b, Fig. 2, adapted to permit the pins or projections 2^b to slide therein. Thus to adjust loop 11 along bar 2 they are turned with respect to each other until 35 pins or projections 2^b align with slot 11^b, and then either the bar and loop is slid along the other and the pins turned down, as in Fig. 1, to prevent sliding of the bar along the loop. By this means the wearer can attach the bar 40 2 in a suitable position to his trouser-waistbands, and by adjusting loop 11 along the bar can cause the suspender-strap end to be adjusted around his waist more or less to effect the holding of the trousers more or less toward the front or side, as he may desire. 45

My invention is not limited to the details shown and described, as they may be varied without departing from the spirit thereof.

Having now described my invention, what 55 I claim is—

1. In suspenders the combination of the straps, with bars, means for connecting the bars with the straps, clamps or grips carried by the bars for connection with trousers, said 60 clamps or grips being provided with sockets in their edges adapted to receive the shanks or holding-threads of buttons on trousers, substantially as described.

2. In suspenders the combination of the straps, with bars, means for connecting the 65 bars with the straps, clamps or grips carried by the bars for connection with trousers, said clamps or grips having sockets located on the side edges of their outer walls to receive the shanks or holding-threads of buttons, substantially as described. 70

3. In suspenders the combination of the straps, with bars, loops for connecting the bars with the straps, means interposed between the bars and loops for holding the loops in adjusted positions along the bars, and clamps or grips carried by said bars and adapted to grip trousers, one of said clamps or grips being adjustably connected with said bar to permit adjustment of the same along the bar, 80 substantially as described. 75

4. In suspenders the combination of the straps, with bars, means for connecting the bars with the straps, clamps or clips carried by said bars to engage trousers, one of said 85 clamps or clips being mounted to slide adjustably upon the corresponding bar by means of a pin-and-slot connection between the bar and said clamp or clip, substantially as described. 90

5. In suspenders the combination of the straps, with bars, means for connecting the bars with trousers, means for connecting the bars with the straps, and means to permit adjustment of the bars laterally with respect 95 to the straps and for maintaining the bars in such adjusted positions, substantially as described.

6. In suspenders the combination of the straps with bars provided with projections, loops mounted movably upon the bars and adapted to rest between a pair of projections and provided with means to permit the loop to be slid along the bar past the projections and to be retained in adjusted position on the 105 bar by the projections, and means for connecting said loops with said straps, substantially as described. 100

7. In suspenders the combination of the straps, with bars provided with means for attachment to trousers and having a plurality of projections, a loop mounted to slide upon each bar, said loop having a slot to permit the passage of the loop along the bar past the projections when the loop is turned in one position, said projections being arranged to limit the movement of the loop along the bar when the loop is turned in another position, and means for connecting said loops with said straps, substantially as described. 110 115

8. In suspenders the combination of the straps, with bars, means for connecting the straps with the bars, clamps or grips carried by the bars comprising yoke-like members provided with a spring and with a clamping-lever, whereby the clamps may be attached 120 125

to trousers, said members being connected with the bars at their lower portions so that the bars will be connected when the members are on a waistband, substantially as described.

9. In suspenders the combination of the straps, with bars provided with means for attachment to trousers, loops carried by said bars and provided with eyes, and clips pivotally carried by the straps adapted to enter

the eyes of said loops for detachably connecting the straps with the bars, said bars having projections to limit the movement of the loops along the bars, substantially as described.
